UNITED STATES PATENT OFFICE.

THOMAS H. SEELY, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

UPPER-PULLING MECHANISM.

1,305,218.

Specification of Letters Patent. Patented May 27, 1919.

Application filed August 17, 1916. Serial No. 115,535.

To all whom it may concern:

Be it known that I, THOMAS H. SEELY, a citizen of the United States, residing at Malden, in the county of Middlesex and 5 State of Massachusetts, have invented certain Improvements in Upper-Pulling Mechanism, of which the following description, in connection with the accompanying drawings, is a specification, like reference characters 10 on the drawings indicating like parts in the several figures.

This invention relates to upper pulling mechanism and more particularly to grip controlling means, being herein embodied in 15 the gripper mechanism of a well-known type of shoe lasting and tacking machine.

An object of the invention is to enable the gripper, with certainty, to maintain control of the upper after pulling and until control 20 is assumed by some other instrumentality, as a wiper or a tack inserting mechanism. An important feature of the invention consists in the combination of an upper stretching gripper and a coöperating wiper, tacking 25 means, or the like, with novel means for relatively operating the gripper and the coöperating means to maintain continuous or uninterrupted control of the stretched upper.

This invention is herein shown, for purposes 30 of explanation, as embodied in a hand method lasting machine in which it has been successfully employed. In that machine the gripper has imparted to it a jaw closing movement to seize the upper stock, 35 an updrawing movement to pull or stretch the upper, and an overdrawing movement to carry the margin of the stretched upper over the shoe bottom preparatory to its being tacked to the innersole. The machine has 40 also a combined wiper and tack block which is operated to follow the gripper in its overdraw movement to rub or wipe the upper over the innersole and hold it in position to be tacked. Economy of upper stock requires 45 that the gripper should give place to the advancing wiper in order that a tack may be inserted in suitable relation to the edge of the shoe bottom. In short, undersized or inelastic uppers the grippers can overdraw but 50 a very short distance and the tack must be driven into the identical portion of the stock which has been held by the gripper jaws.

To render the grippers self adaptable to different stock conditions the overdraw movement is yieldingly effected and thereby 55 made variable in length to take up whatever length of stock has been updrawn. Inasmuch as the combined wiper and tack block follows the gripper automatically during the overdraw it has been necessary in rapidly 60 operated power driven machines to open the gripper jaws at an early stage in the overdraw movement in order that, while pulling an inelastic upper, they should get out of the way of the wiper. The practical result 65 has been that there has occurred a loss of tension on the upper between its release by the grippers and its complete control by the wiper. In a more particular aspect this invention consists, for the purpose of over- 70 coming this loss of tension, in means for causing the gripper jaws to retain frictional engagement with the upper after the pulling grip on the upper has been relieved. This organization allows the upper to slip between the jaws, if it is short, during the overdraw movement and permits deferring 75 of the final opening of the jaws until the wiper has advanced far enough to insure no loss of tension in the stretched upper. The 80 mechanism herein shown as employed for operating the gripper includes, in addition to a jaw closing means, a jaw holding means to which control of the jaws is transferred for the overdrawing movement of the gripper. As I am advised, this combination is 85 broadly new.

The foregoing and other features of the invention, including certain details of construction and more important combinations of parts, will be better understood from the following description of the illustrative machine with the aid of the accompanying drawings and the invention will then be more particularly pointed out in the claims. 90

Figure 1 of the drawings shows a left hand side elevation of a well-known lasting and tacking machine equipped with improvements embodying the present invention. 95

Fig. 2 is an enlarged similar side elevation of the gripper jaw closing and holding mechanism.

Fig. 3 is a perspective view of said mecha-

nism showing the connections extending to the gripper.

Fig. 4 is an enlarged front elevation of the jaw closing mechanism.

5 Fig. 5 is a similar rear elevation of the jaw holding mechanism.

Fig. 6 is a detail view showing the gripper positively holding and tensioning the upper;

10 Fig. 7 is a similar view showing the wiper advancing over the shoe bottom and the upper slipping from between the gripper jaws while held under tension.

The grippers are indicated at 2 and are or may be of the construction disclosed in 15 United States Letters Patent No. 1,005,234, granted Oct. 10, 1911, on application of Ladd and McFeely. The grippers are suspended from an updraw lever 4 which receives its working movement from the cam 20 shaft through a spring 5, and are embraced by a yoke 6 on the front end of the overdraw rod 8 which receives its working movement from a spring 10, all shown in Fig. 1 and having the construction and arrangement 25 common in this type of machine, an example of which may be seen in Ladd and McFeely Patent No. 584,744.

The closing bar 15 of the gripper, which is normally upraised by the jaw opening 30 spring 16, is overlaid by an arm 20 of a rock-shaft 22 mounted in bearings on the updraw lever 4 and having a second arm 24, Fig. 4, pivotally supporting a roll carrier 25 that transmits jaw closing movement yieldingly 35 through spring 26 from closing cam 28 on the main cam shaft 30.

In the rear of rock-shaft 22 of the jaw closing mechanism is the rock-shaft 32 of the jaw holding mechanism, carried in a bracket 40 33 secured to the machine head. An arm 34 is clamped on a sleeve 35 on the rear end of rock-shaft 32 and carries a roll that receives motion from a cam 38 adjustably secured at 37, Fig. 5, to a hub on the main cam shaft 30. 45 This motion is transmitted from arm 34 and its sleeve 35 to the rock-shaft 32 yieldingly by a spring 36 one end of which engages a collar 39 rigid with rock-shaft 32 and the other end of which is secured to an adjusting lever 42 that is pivoted on the shaft and has a pawl and ratchet engagement at 37 50 with the sleeve 35, as shown in Fig. 2. A second arm 40 is rigidly secured to jaw holding rock-shaft 32 and its free end is 55 forked, Figs. 3 and 5, to embrace a roll 44 on the rear side of the arm 24 of jaw closing rock-shaft 22. The jaw holding cam 38 is set with its effective high portion angularly behind the effective high portion of the jaw 60 closing cam 28, as illustrated in Fig. 4.

This construction and organization provides that the jaws shall be closed by the cam 28 and held during the updraw or upper stretching movement of the grippers after 65 which the high part of cam 28 shall pass

from under the roll arm 24. In the old machine this would have allowed spring 16 to open the jaws in the early part of the overdraw in order that the grippers might get out of the way of the wiper if the upper 70 were short or inelastic. In accordance with the new organization the control of the jaws passes, as shown in Fig. 4, from the closing cam 28 to the holding cam 38 through arm 40, rock-shaft 32, spring 36 and arm 34. 75 The spring 36 is maintained at a tension which will hold the jaws in engagement with the stock and allow the stock to slip from between them during the overdraw if the stock is short or inelastic. The holding cam 80 38 is maintained in angular adjustment, at 37, to hold the jaws lightly closed during all or any desired part of the overdraw.

The combined wiper and tack block 50, through which the driver 52 operates, is advanced toward the right in Fig. 1, by connections (not shown) with cam shaft 30, closely following the grippers during the overdraw and laying the stretched upper down upon the innersole in position to be tacked. If the upper is short or inelastic, so that there has been a short updraw and there is a narrow margin to carry over in the overdraw, the upper will begin to slip between the jaws 90 early in the overdraw but the jaws will retain frictional engagement and control of the upper throughout the overdraw or until it has pulled entirely out of the jaws, and the gripper will thereby coöperate with the wiper to manipulate the upper into tacking 95 position without loss of tension. If the advancing wiper should in any instance overtake the overdrawing gripper and engage it no harm will occur for the wiper will push the gripper ahead of it, causing the upper to 100 slip faster from between the jaws, whereas if the jaws were holding the upper with the force of the closing mechanism collision between the wiper and gripper would batter those parts and be liable to tear out the portion 105 of upper held by the jaws.

The greater thickness of the upper materials of the toe portion of some shoes than of the sides renders it desirable on some work to reduce the tension of spring 36 while 115 lasting the toe. This can be done by lever 42 and inasmuch as the time for this adjustment is coincident with the time for making well-known adjustments of the grippers for plaiting the toe this invention includes 120 connections, not shown, from the known plaiter controlling mechanism to the spring 36 to make the spring adjustment automatically.

Having explained the nature of this invention and described how it may be employed, I claim as new and desire to secure by Letters Patent of the United States:—

1. In a machine of the class described, the combination of an upper stretching gripper, 130

a coöperating wiper, and means for operating the gripper to maintain continuous control of the gripped portion of the upper during the advance of the wiper first by a 5 positive grip and later by a slipping grip.

2. An upper pulling machine having, in combination, a gripper and operating mechanism therefor organized to cause the gripper to seize and pull the stock and then to 10 carry it toward position to be fastened, said mechanism being constructed and arranged to relieve the grip of the gripper jaws on the stock for the carrying over movement and to retain frictional engagement of the 15 jaws with the stock during such movement.

3. An upper pulling machine having, in combination, a gripper, means to close the gripper jaws, and other means to the control of which the gripper jaws pass from the 20 closing means and which operates to hold the jaws upon the work with lighter pressure than that applied by the closing means.

4. An upper pulling machine having, in combination, a gripper having upper seizing 25 jaws, and jaw operating means organized to close the jaws and maintain a grip for a portion of the cycle of the machine and then to hold the jaws closed with a lighter pressure to allow the upper to slip 30 between the jaws during a succeeding portion of the cycle.

5. An upper pulling machine having, in combination, a gripper having upper seizing jaws, means to close the jaws, means to 35 raise the gripper to stretch the upper, means to move the gripper outward to overdraw the upper, and means arranged to take control of the jaws during the overdraw and hold them on the upper with a pressure 40 lighter than the pulling grip and adapted to allow them to draw off the upper during the overdraw.

6. In an upper pulling machine, a gripper, a gripper jaw closing mechanism, upper 45 drawing means, overdrawing means, and a jaw holding mechanism to the control of which the closing mechanism gives over the jaws during the overdraw.

7. In an upper pulling machine, a gripper 50 and a gripper jaw closing mechanism comprising a rock-shaft having one arm operatively connected with the gripper, a second arm, a cam roll, a roll carrier pivoted to the second arm, and a closing pressure 55 regulating spring operatively arranged between the second arm and the roll carrier.

8. In an upper pulling machine, a gripper and gripper jaw controlling mechanisms comprising jaw closing means and additional means arranged to become operative 60 subsequently to hold the jaws closed with lighter pressure than the closing pressure.

9. In an upper pulling machine, a gripper and gripper jaw controlling mechanisms 65 comprising a stiff spring through which jaw

closing pressure is applied and a lighter spring through which jaw holding pressure is applied.

10. In an upper pulling machine, a gripper and gripper jaw controlling mechanisms 70 comprising a stiff spring and a cam to apply jaw closing pressure through the stiff spring, a light spring and a second cam arranged to become operative before the end of the throw of the first cam and to apply 75 holding pressure to the jaws through the light spring and the arm after the end of the throw of the first cam.

11. In an upper pulling machine, a gripper to updraw and overdraw the upper, 80 a wiper to follow the gripper during the overdraw and lay the upper upon the inner-sole, and grip controlling means organized to close the jaws and hold them firmly upon the upper during the updraw and to hold 85 them less firmly during the overdraw so that the upper can slip from them as the wiper advances.

12. In an upper pulling machine, a gripper to updraw and overdraw the upper, and 90 grip controlling means organized to close the jaws and hold them firmly upon the upper during the updraw and to hold them less firmly during the overdraw so that the upper can slip from them. 95

13. In an upper pulling machine, a gripper to updraw the upper, a wiper to lay the upper over the shoe innersole, and grip controlling means organized to hold the jaws firmly upon the upper during the updraw 100 and to hold the jaws with a definitely less pressure during the advance of the wiper and allow the upper to slip out as the wiper advances.

14. In an upper pulling machine, a gripper to updraw the upper, a wiper to lay the upper over the shoe innersole, grip controlling means organized to hold the jaws firmly upon the upper during the updraw and to hold the jaws with a definitely less pressure during the advance of the wiper and allow the upper to slip out as the wiper advances, and means to adjust definitely the pressure with which the jaws are held during the advance of the wiper. 115

15. In an upper pulling machine, a gripper controlling mechanism comprising a strong spring to close the gripper jaws, a weaker spring, and means operating to transfer control of jaws from the strong 120 spring to the weaker spring at a predetermined point in the operation of the machine.

16. In an upper pulling machine, a gripper controlling mechanism comprising a strong spring to close the gripper jaws, 125 a weaker spring, means operating to transfer control of the upper holding function of the jaws from the strong to the weak spring, a wiper, and means to operate the wiper to push the jaws toward the edge of the upper. 130

17. In a step by step lasting machine, a gripper and a wiper operating in timed relation to stretch a portion of upper over the edge of a last and then to wipe it down upon the last bottom, and an edge gage to determine the position of the shoe in the path of the wiper, combined with a gripper operating mechanism organized to prolong the action of the gripper on the margin of the stock for a substantial length of time after the wiper has begun to wipe down the stock between the edge of the last and the gripper.

18. In a step by step lasting machine, a gripper and a wiper operating in timed relation to stretch a portion of an upper over

the edge of a last and then to wipe it down over the last bottom, and an edge gage to determine the position of the shoe in the path of the wiper, combined with a gripper 20 operating mechanism organized to relieve without releasing the gripping hold of the gripper on the stock during the advance of the wiper over the stock in such manner that the gripper continues to maintain control of the edge of the stock during a substantial portion of the movement of the wiper over the last bottom.

In testimony whereof I have signed my name to this specification.

THOMAS H. SEELEY.
